WALTER A. CLARK, OF BRANTFORD, ONTARIO, CANADA, ASSIGNOR TO SLINGSBY
MANFG. CO. LTD., OF BRANTFORD, ONTARIO, CANADA.

SHUTTLE-BOX-SELECTING MECHANISM FOR LOOMS.

1,077,904.

Specification of Letters Patent.

Patented Nov. 4, 1913.

Application filed November 14, 1907, Serial No. 402,180. Renewed April 4, 1913. Serial No. 758,965.

To all whom it may concern:

Be it known that I, WALTER A. CLARK, a citizen of the Dominion of Canada, and residing at Brantford, in the Province of Ontario, Canada, have invented certain new and useful Improvements in Shuttle-Box-Selecting Mechanism for Looms; and I hereby declare the following to be a full, clear, and exact description of the invention, such as will enable others skilled in the art to which it pertains to make and use the same.

My invention relates to color-selecting mechanism for looms and especially to mechanism of this character which is employed in blanket-weaving looms. Certain features of the invention are especially applicable to the weaving of blankets having a considerable area of solid color, as white, with colored borders. The selecting mechanism which is most ordinarily employed with looms of this type comprises a chain carrying at desired intervals rollers which bring into contact gears to which are attached hooks for lifting the shuttle box to bring the shuttle having the desired color of weft therein in operative relation to the picking stick, together with means for disengaging the gears and altering the position of the shuttle box when the selected shuttle has made the necessary number of vibrations. This mechanism is heavy, expensive, and liable to derangement.

The object of my invention is to provide selecting mechanism of this character which is simple, efficient, relatively inexpensive, and which will permit the pattern to be changed with comparative ease. I realize these objects by the embodiment of my invention disclosed in the drawings forming a part thereof, wherein—

Figure 1 represents a side elevation of my mechanism, showing the connections between the same and a moving part of the machinery and indicating the connections between the same and the shuttle box. Fig. 2 represents a front elevation of my mechanism, the operating shaft and the bell crank connections with the shuttle box being omitted. Fig. 3 represents a top plan view of the selecting drum, operating levers for the shuttle box, and associated parts. Fig. 4 represents an enlarged detail of a modification of the drum construction shown in the preceding figure. Fig. 5 represents a

side elevation of one of the selecting rings shown in Fig. 4 and Fig. 6 represents a modification of the means for operating the shuttle box from the selecting drum. Fig. 7 is a view in elevation of an old and well known type of shuttle lifting mechanism. Fig. 8 is an end view of the same. Fig. 9 is a section on line 9—9, Fig. 7.

Describing the parts by reference characters, 1 represents a drive shaft for the selecting mechanism, and 2 a portion of the frame of the loom, said portion being provided with a journal for the drive shaft and with a pair of brackets 3 for the selecting mechanism.

4 denotes an eccentric with which shaft 1 is provided and 5 an eccentric strap thereon connected with a link 6, the upper end of which is pivotally connected to a bell crank lever 7 which is journaled on a shaft 8 supported by bracket members 3. The vertical arm of bell crank lever 7 has pivoted thereto a pawl 9 coöperating with the ratchet wheel 10 which is rigid with shaft 8. The lower end of the pawl is provided with a lug 9^a which rests against the face of the ratchet wheel and assists in retaining the pawl in proper relation to said wheel.

11 denotes a selecting drum which rotates with the shaft 8, being suitably secured thereto. This drum is provided on its convex surface with circumferential rows of lugs or pins 12. Four such rows are shown, but it will be evident that a greater or less number of rows may be employed, depending upon the variety of colors which will be used in the particular pattern to be woven.

A shaft 13 extends across the top of the drum, the shaft being supported by the bracket arms 3. On this shaft are journaled bell crank levers 14, the lower ends of which bear upon the surface of the drum 11 and are of considerable circumferential extent with respect to said drum, for a purpose to be hereinafter explained. On a shaft 15, which may be supported in any suitable manner, there is mounted a corresponding number of bell crank levers 16. The vertical arms of these levers are connected to the vertical arms of levers 14 by means of links 17. These links may be adjusted to various positions on the vertical arms of levers 14 and 16 for the purpose of varying the throw of the former levers upon the shuttle-box mechanism. For the purpose of

such adjustment, levers 14 and 16 are provided with downwardly inclined notches 18 and 19 respectively, which notches are adapted to receive loops 20 and 21 carried by opposite ends of links 17 respectively. The other or horizontally extending arms of levers 16 are each provided with a rod or link 22 which is connected with the mechanism ordinarily employed for the purpose of operating the shuttle box. A well known form of this mechanism is illustrated in Figs. 7, 8 and 9, wherein *a* represents a shaft which is secured in the bed of the machine, and on said shaft are mounted a horizontally arranged series of levers *b*, *b'*, *b²* and *b³*. Each lever is secured to one of the rods 22 intermediate its ends, as at *c*, and on the free end of each lever is mounted a gear wheel *d*, *d'*, *d²* and *d³*. On a shaft *e* secured on the bed of the frame is mounted a large gear *f*, and the arrangement is such that any of the gears *d*, *d'*, *d²* and *d³* can be drawn up and caused to mesh with said gear *f*. The said gear *f* is operatively connected with other portions of the machine so that it is driven all the time the machine is in operation. To the gears *d*, *d'*, *d²* and *d³* are connected rods *g*, *g'*, *g²* and *g³* respectively by means of crank pins. To the rod *g* is secured a lever arm *h*, the lower end of the said lever arm *h* being pivotally supported from the bed of the machine, at *l*. To the rod *g'* is secured a lever arm *h'* which is pivoted to the machine at *l'* and the free end of said lever arm carries a sheave *m*. To the rod *g²* is secured a lever arm *h²* which is pivotally supported from the bed of the machine at *l²* and the lower end of the lever arm *h²* carries a sheave *m'*. To the rod *g³* is secured a lever arm *h³* and the lower end of said arm is pivotally supported from the bed of the machine at *l*. A pair of sheaves *p* are rotatably mounted on the bed of the machine, and a cable *n* is secured to the lever arm *h'* and is then carried over the sheave *m*, then over one of the sheaves *p* and the lower end is secured to the shuttle box frame *r* containing the shuttles *s*. A second cable *o* is secured to the lever arm *h³* and is then carried over the sheave *m'*, then over the other sheave *p* and its end is secured to the shuttle box. Now, when it is desired to bring the first shuttle into position the lever *b* is raised, when it is desired to bring the second shuttle into position the lever *b'* is raised, when it is desired to bring the third shuttle into position the levers *b* and *b'* are raised together and when it is desired to bring the fourth or bottom shuttle into position the levers *b²* and *b³* are raised together. As each lever is raised the gear on the end thereof will be brought into contact with the large gear *f* and the rods connected to the gears will be actuated which in turn will operate the lever arms

connected to said rods, thereby drawing up the cables *n* and *o*, which in turn draw up the shuttle box frame. This head motion forms no part of my invention, it being old in the art to operate the shuttle-boxes by working jacks of vibrated gears.

In Fig. 4, I have shown a detail of a modification of the drum 11. In this modification, the drum 11^a is shown as a wheel having at one lateral edge thereof an outwardly projecting circumferential flange 23 provided with ratchet teeth, constituting a ratchet wheel similar to ratchet wheel 10 for the purpose of operating the drum. In place of the circumferential rows of teeth 75 or lugs with which drum 11 is provided, I apply to the surface of the wheel a suitable number of toothed wheels or rings 24, said rings being secured to the wheel as by means of screw bolts 25. These rings will be provided with teeth so arranged as to engage the lower ends of levers 14 and thereby cause said levers to operate the shuttle box to automatically select for operation a shuttle having the desired color of weft thereon 80 to enable the desired pattern to be woven into the blanket.

It will be observed that the ratchet 10 is provided with a recess 10^a in which the toe of pawl 9 rests in Fig. 1 and that one end 95 of shaft 8 is provided with an operating handle 8^a. The purpose of this recess is to permit of the oscillation of the lever 7 by the drive shaft 1 without any corresponding operation of the selecting drum during the 100 time that it is desired to employ a solid pattern of white or other color in the blanket. When it is desired to apply the border to the blanket, the operator throws the handle 8^a to move the recess 10^a out of register with 105 pawl 9, whereupon the oscillation of lever 7 causes the drum to be rotated, and the pins or lugs thereon will oscillate levers 14 to cause the automatic selection of the shuttles having the various colors of weft thereon. 110 It will be observed, from Fig. 1, that the lower or bearing ends of levers 14 are of considerable circumferential extent. This is for the purpose of enabling a pin or lug which lifts the lower end of said lever to 115 "dwell" thereunder a sufficient time to enable the appropriate shuttle to be vibrated back and forth before the pin or lug passes from beneath the foot of the lever.

In Fig. 6, I have shown a modification of 120 the connection between the drum and the mechanism which operates the shuttle box. The connection shown in this figure is intended to take the place of both sets of levers 14 and 16 and the connections therebetween. The lever 26 shown in this view is provided with a journal 27 for the reception of shaft 14 and is provided with a downwardly extending arm 28 similar to the downwardly extending arms of levers 14. 130

The other arm 29 of lever 26 projects over and beyond the arm 28 and is provided with an aperture for the reception of the link 22 by which connection with the shuttle box operating mechanism is made.

From the foregoing description, the operation of my invention will be clear. Assuming the parts to be in the position shown in Fig. 1, the rotation of shaft 1 will cause 10 no operation of the selecting drum until such time as the necessary amount of solid weft has been supplied. At this time, the operator throws the handle 8^a until the pawl 9 has ridden over the tooth adjacent to said 15 recess, whereupon the operation of shaft 1 will cause the drum to be rotated, and said drum, through the pins or lugs projecting therefrom, will automatically select for vibration the shuttle having the desired color 20 of weft thereon.

Having described my invention, I claim:
In a loom, the combination with a series

of shuttle boxes and means for raising said shuttle boxes, of a rotary drum having thereon a plurality of pins, a ratchet wheel for 25 operating said drum, said wheel being provided with an elongated recess, a pawl adapted to engage said wheel, a series of bell crank levers arranged in proximity to said drum and adapted to be engaged by the 30 pins on said drum, means for connecting the levers with the means for raising said shuttle boxes, means for rotating said drum independently of said ratchet and means for operating said pawl, substantially as specified.

In testimony whereof, I sign the foregoing specification in the presence of two witnesses.

WALTER A. CLARK.
